(57) **CLAIM**

The ornamental design for a twist mop, as shown and described.

DESCRIPTION

FIG. 1 is a side elevational view of a twist mop showing our new design, the opposite side being identical thereto;

FIG. 2 is a front elevational view thereof, the rear being identical thereto;

FIG. 3 is an enlarged plan view as seen for the bottom of FIG. 2

FIG. 4 is an enlarged plan view as seen from the top of FIG. 2; and,

FIG. 5 is an enlarged perspective view of FIG. 1. The handle is shown broken away to indicate indeterminate length.
